UNITED STATES PATENT OFFICE.

HERMAN WINANS BURGER, OF PORT KENNEDY, PENNSYLVANIA.

HEAT-INSULATING COVER.

1,190,857.

Specification of Letters Patent. Patented July 11, 1916.

Application filed March 25, 1915. Serial No. 16,903.

To all whom it may concern:

Be it known that I, HERMAN W. BURGER, a citizen of the United States, and a resident of Port Kennedy, in the county of 5 Montgomery and State of Pennsylvania, have invented a new and Improved Heat-Insulating Cover, of which the following is a full, clear, and exact description.

Among the principal objects which the 10 present invention has in view are: to provide an insulating material in sheet form of uniform thickness; to vary the thickness of an insulating cover by multiplying the number of unit layers employed; to protect 15 in service a cover constructed and arranged in accordance with the present invention; to form a cover as characterized having a cellular structure; and to provide an insulating cover having internal dead-air-containing 20 chambers or cells.

Drawings.—Figure 1 is a top view of a fragment of cover constructed and arranged in accordance with the present invention; Fig. 2 is a section on an enlarged scale showing 25 a unit sheet of said cover prior to the same being pressed or crimped; Fig. 3 is a similar view showing the sheet after same has been pressed or crimped; Fig. 4 is a section of a cover having two thicknesses or 30 sheets united as in service; Fig. 5 is a detail view in cross section showing a half section of a pipe and cover therefor; said cover being constructed and arranged in accordance with the present invention, the view being 35 on a diminished scale. Fig. 6 is a section of a cover having two thicknesses or sheets constructed in accordance with the modified form of the invention. Fig. 7 is a cross section of a half section of a pipe and cover 40 therefor, said cover being constructed and arranged in accordance with the modified form of the invention.

Description.—As seen in the accompanying drawings, a unit sheet is formed, having 45 a relatively thick layer 6 of felt, mineral wool, hair, or other equivalent compound. In the preferred form I employ crude felt. This layer is covered on one surface with a relatively thin layer 7 of asbestos cloth. 50 The layers 6 and 7 are lightly pressed together, being caused to adhere, any suitable adhesive being employed for this purpose. Full-length sheets of the felt layer 6 and of 55 the asbestos layer 7 are employed. After being adhered, as shown in Fig. 2 of the drawings, the sheet is passed through crimping

rollers, the surface whereof is preferably arranged to produce depressions 8 arranged in staggered relation, as shown in Fig. 1 of the drawings. When passing through the rollers, the total layered sheet is complete and forms what is herein styled a single or unit thickness.

Sheets constructed as above described are intended for what may be termed the 65 "body" of the insulating cover. One such sheet is provided, having a light canvas duck layer 9, which is preferably impregnated with a suitable non-inflammable chemical. If the specified insulating cover 70 calls for one thickness or sheet of such covering, the sheet used is the one provided with the outer duck layer 9. If two or more thicknesses or layers be necessary, a cover, such as shown in Fig. 4 of the drawings, is 75 employed. In this cover the two sheets are adhered, a suitable adhesive being placed upon the asbestos cloth layer 7 of one sheet, and the felt of the other sheet being then pressed thereupon. When joining two or 80 more of the unit sheets, care is exercised to overlay the depressions 8 in the juxtaposed sheets, to form, as seen best in Fig. 4 of the drawings, pockets wherein air is immovably trapped, thereby forming what is styled a 85 "dead-air cell."

When the cover composed of two or more thicknesses or unit layers is employed, it is attached to the protected article by any suitable adhesive. When so installed, the 90 outer surface of the cover is protected against abrasive wear by the duck layer 9.

While I have herein described and have shown in the accompanying drawings the cover in sheet form, it will be understood 95 that the compiled material may be shaped to any suitable form, such as is conventionally employed for covering pipes of either heating or refrigerating plants. It will also be understood that when desired the 100 cover may be pressed into suitable shapes, to be employed as a removable cover for surfaces, to retard the too rapid radiation thereof, as, for instance, the surface of an automobile engine hood, which it is desired 105 in certain weather to protect from too rapid radiation. The insulating cover, when formed in sheets, is suitable for lining steel passenger or freight cars, and is more especially employed for the lining of refrigerating cars. It will also be understood that 110 while I have herein shown the layers 6 and

7 as having a certain relative thickness, this may be varied to suit the exigencies of employment, the desire of the owner, or the fancy of the designer.

5 Claims:

1. A cover as characterized, comprising a layer of inflammable fiber; a layer of non-inflammable fiber, said layers being formed as a homogeneous sheet, said sheet being 10 pressed to form surface depressions therein, said depressions being formed in opposite surfaces of said sheet; and a protective layer for said sheet, constructed from a woven fabric permanently attached to said 15 sheet and to the outer surface thereof.

2. A cover as characterized, comprising a layer of inflammable fiber; a layer of non-inflammable fiber, said layers being formed as a homogeneous sheet, said sheet being 20 pressed to form surface depressions therein, said depressions being formed in opposite surfaces of said sheet; and a protective

layer for said sheet, constructed from a woven fabric permanently attached to said sheet and to the layer of non-inflammable 25 fiber thereof, said protective cover being indented in correspondence with said sheet.

3. A cover as characterized, comprising a plurality of unit sheets, each embodying superposed layers of inflammable fiber and 30 non-inflammable fiber homogeneously united and indented to form pockets in the surfaces thereof, said sheets being adhered in superposed relation, and the pockets thereof being superposed to form internal 35 cells.

In testimony whereof I have signed my name to this specification in the presence of two subscribing witnesses.

HERMAN WINANS BURGHER.
